Urbana, Ill.

Application July 27, 1945, Serial No. 607,416

15 Claims. (Cl. 250—27)

1

This invention relates to electronic induction accelerator apparatus, and more particularly to means for improving the yield of charged particles, as electrons, by the provision of means varying the relative radial field strength as a function of time.

This invention relates in general to magnetic induction accelerator devices which comprise an evacuated doughnut-shaped tube, as of glass or porcelain with means (as a heated filament) for periodically introducing electrons or other charged particles into the tube; magnetic means for causing the charged particles to circulate in an orbit in the tube for a very large number of turns, accelerating them continuously during this circulation, this means comprising magnets above and below the tube with pole faces of outwardly tapered or divergent configuration, with means for increasing the magnetic field continuously during the circulation of the charged particles; and means for utilizing the kinetic energy of the charged particles, as a target which they may strike to create X rays. The circulating charged particle has a centripetal force requirement varying with the radius of its orbit, and the pole face tapered configuration or divergence is such as to provide a magnetic holding force also varying as a function of the radius, the equilibrium orbit of the charged particle having a radius where these forces are equal.

The general principles of operation of a magnetic induction accelerator are known to the art and have heretofore been published in various patents and publications, particular reference in this regard being made to Kerst Patent 2,297,305 of September 29, 1942, and an article entitled "The betatron," by D. W. Kerst, which appeared in vol. 10, No. 5, of the American Journal of Physics (October, 1942). Magnetic induction accelerators of this type have also been the subject of a number of other patents and publications including the following: Slepian Patent 1,645,304; Steenbeck Patent 2,103,303; Smith Patents 2,143,459 and 2,289,220; Penney Patent 2,193,602; Baldwin Patent 2,331,788; Kerst Patent 2,335,014. Other articles by D. W. Kerst are: "The acceleration of electrons by magnetic induction" which appeared in vol. 60, No. 1, of The Physical Review (July 1, 1941) and "A 20-million electron-volt betatron or induction accelerator" which appeared in vol. 13, No. 9, of The Review of Scientific Instruments (September, 1942).

One feature of this invention is that it varies the relative radial field strength or radial field distribution as a function of time, very materially

2

and rapidly altering the radial field strength relationship at and about the equilibrium orbit at the beginning of each period of operation of the betatron, the arrangement being such that the variation of radial field shape from a smooth curve is gradually released or tapered off until it is substantially negligible at or near the end of the acceleration period.

This variation in radial field shape or relative radial field strength as a function of time provides several advantages in the operation of an induction accelerator of this type. One such advantage is that it very substantially increases the yield of X rays where the device is being used for the generation of X rays, for example. This advantage results from the fact that a very materially great number of electrons or other charged particles injected into the tube are accelerated radially toward the equilibrium orbit fast enough to prevent loss of charged particles by collision with the injector mechanism, or otherwise, and to result in a 50% or greater increase in the number of charged particles which are brought into the equilibrium orbit and accelerated up to the desired velocities. Another advantage of this invention is that it provides a magnetic induction accelerator with much greater radial stability of the charged particles in their orbital circulation, much more quickly dampening down radial oscillations of the charged particles. Another advantage of this invention is that the very much greater radial acceleration toward the equilibrium orbit, and greater radial stability of circulation, is tapered off or "relaxed" toward the end of the acceleration period, when such effects are no longer desirable, to enable desired axial or vertical stability to be secured and particle path to be changed at the end of the acceleration period to cause the charged particles to impinge on a target or otherwise produce the desired effect.

Other features and advantages of this invention will be apparent from the following specification and the drawings, in which:

45 Figure 1 is a side elevational view of a magnetic induction accelerator embodying my invention; Figure 2 is a horizontal sectional view along the line 2—2 of Figure 1; Figure 3 is an end elevational view of such apparatus; Figure 4 is a fragmentary vertical view, along the line 4—4 of Figure 2; Figure 5 is an enlarged fragmentary sectional view of the injector structure; and Figure 6 is a circuit diagram of one particular form of my radial field shape varying arrangement.

Inasmuch as the general principles of operation of a magnetic induction accelerator have been fully described in the patents and publications listed above, the description of the general construction and operation of the betatron will be kept brief, and reference may be made to such other publications to supplement this general description if desired.

In the particular embodiment illustrated here-with the tube providing the annular chamber in which the charged particles circulate is here identified as 10, and is provided at one point in its periphery with injector means here identified as 11. The tube is preferably made of porcelain for ease in formation, as is more fully described and claimed in the copending application, now abandoned, of Almy and Hursh, Serial No. 596,460 filed May 29, 1945, although it may be made of glass or any other suitable material; and it is preferably coated on the inside with a high resistance conductive coating, as with a very thin film of palladium. The tube is disposed between two generally circular pole pieces here identified as 12 and 13, these pole pieces being of outwardly tapered or diverging configuration, as may be best seen in Figure 4, and substantially coaxial with the tube 10, such that the field strength diminishes radially toward the outside of the annular chamber, and so that the flux lines curve in a vertical plane to provide the desired vertical stability and damping of vertical oscillations of the charged particles when moving in their circular path. As has been more fully described in the above-mentioned patents, and particularly Kerst Patent 2,297,305, the outwardly tapered configuration of the pole piece faces is such that the magnetic field strength varies inversely with the radial displacement r according to the proportionality

$$H \propto \frac{1}{r^n}$$

where n is a constant between zero and unity. This constant has heretofore been preferably kept, by proper design, between .5 and .8, generally in the neighborhood of .75; but by the use of my radial field shape varying means, pole face design may be used with a constant down near zero and even into the negative range, this range being included when n is hereinafter termed as being less than unity. In the space in the center of the torus or annular tube is means also comprising a factor in the field shape and strength relationship, this comprising a pair of disks 14 and 15 of magnetically permeable material, and an intermediate spacer of non-magnetic material, as stone or insulating material.

Surrounding the pole pieces 12 and 13 are the main field producing coils 17 and 18. Surrounding all of the parts just described is a frame structure of iron or other magnetically permeable material completing the magnetic circuit, this comprising top, bottom, and side portions and being here identified in general as 19. The magnet coils 17 and 18 are energized by an alternating current of considerable amplitude, these coils preferably being connected in parallel with condensers and energized from an alternating current generator, which may have a frequency of 180 cycles per second and is preferably above the conventional 60 cycles per second, the magnet coil and condenser providing a resonant circuit at this frequency in which high currents circulate, the generator merely providing the actuating current replacing losses in the system. The electron injecting mechanism is intended, as by excita-

tion of a thyratron grid by voltage from a pick-up or peaking strip in the field of the main magnet coils, to inject the electrons into the tube at the beginning of the rising quarter cycle of current on the positive side of the cycle. By the electron gun or injector means shown in Figure 5 and more fully described hereafter, the electrons are injected into the tube substantially tangent to the circular path provided, with substantial initial energy of more than several hundreds electron volts. Coaction between the moving electrons and the vertical lines of force of the magnetic field cause them to be accelerated radially by the magnetic force, inwardly if the injector means is outside of the equilibrium orbit. At the same time, the increasing magnetic field accelerates the electrons in their orbital path. The period of acceleration of speed of electrons continues during the entire rising portion of the positive cycle of the current, as the magnetic field is increasing during this time; and since the electrons may have described several thousand revolutions in this time, strong magnetic fields will have worked their energy up to millions of electron volts. At the end of this time means is used to swing the electrons out of their equilibrium orbit, as by a change in the distribution of magnetic field, into collision with a target, for example. During the time the electrons are describing revolutions in and about the equilibrium orbit, maintenance of the electrons at and near the equilibrium orbit is effected, in the case of radial stability, by proportioning of the field relationships such that the average flux density throughout the area within the orbit is double the flux density at the orbit; and vertical or axial stability is secured by the curvature of the lines of force in a vertical plane.

Referring now more particularly to Figure 5, the tube 10 will be seen to have a neck portion 10a to which is sealed the body of the tube 11. This tube is provided with concentric generally cylindrical wall portions 11a, 11b and 11c, and with a vacuum nipple 11d. The walls 11b and 11c serve as supporting means for the electron gun structure comprising as its principle parts the hot cathode or filament 11e, shielding means therefor comprising inner and outer shields 11f and 11g, and the supporting and connecting rod members. The filament 11e is caused to emit electrons at the desired instant, as by actuation of a thyratron as mentioned above to complete a circuit effecting application of appropriate negative potential, as 10,000 volts, to the inner shield 11f and the filament 11e, so that these parts are highly negative with respect to the grounded inner coating of the tube and outer shield 11g; this differential causing electrons to be emitted through the shield slit 11g, streaming to the left as viewed in Figure 5, with an initial velocity in the order of several thousand electron volts. These electrons are acted upon by the magnetic field in such a manner as not only to accelerate their velocity but also to tend to accelerate them inwardly toward the center of the tube, toward the equilibrium orbit 10b, which is preferably just to the inside of the electron gun structure in the form shown in the drawings. The electrons are then caused to travel around in or near the equilibrium orbit for as many revolutions as may be desired, and are finally caused to follow an instantaneous orbit of slightly greater radius than the equilibrium orbit and to impinge upon a target 11h; this impingement effecting the desired generation of X rays, as is more fully

described and claimed in the copending Kerst and Serber application Serial No. 534,060, filed May 4, 1944, now U. S. Patent 2,447,255.

It will be apparent that, in order to avoid loss of electrons and poor yields as a result of electrons impinging upon the electron gun structure when they have only revolved a couple of times or so and have no substantial energy, the electrons initially injected or emitted by the gun must be accelerated inwardly, in the first few revolutions, sufficiently to miss the target. The electrons initially oscillate rather considerably about their instantaneous orbit, being to the inner side of the instantaneous orbit at the end of their first trip around the tube so that the time of at least two revolutions is provided within which to effect a sufficient inward acceleration or average change of instantaneous orbit such that they will miss the target and back of the shield on the second revolution. If this can be accomplished, and the field strength relationships are proper radially, the electrons will then continue traveling in instantaneous orbits getting closer and closer to the equilibrium orbit. In the particular induction accelerator which I am describing here the equilibrium orbit has a radius of about 7½ inches and the size of the electron gun parts are such that the electrons must be accelerated inwardly about two millimeters in the first two revolutions, i. e., the electrons must be accelerated radially inwardly through a distance of the order of two millimeters in about $\frac{1}{100}$ of a microsecond.

I have found that the relative radial field strength relationships, or radial field shapes, heretofore used in magnetic induction accelerators are not satisfactory for this purpose and not capable of producing high yields, even though these relationships may be satisfactory in theory when the electron is already in the equilibrium orbit. I have found that much higher yields may be obtained by the use of radial field shapes which are not proportional, particularly at and near the instant of injection, to

$$\frac{1}{r^n}$$

with n a constant. I still find it convenient to have the conditions at the equilibrium orbit such that the flux density at that point is only half the average flux density within the area of the orbit; but I find it results in much improved yield and radial stability to have the field strength immediately within and without the equilibrium orbit considerably different from that which would be indicated by the above proportionality, at least at and about the equilibrium orbit and for at least the early portion of the period of rising magnetic strength. Generally speaking, I have found that it is desirable to have the field strength outside the desired equilibrium orbit, and at least as far as the point where the electrons are injected, substantially stronger than would be indicated by the above proportionality; and to have the field strength immediately within the equilibrium orbit substantially less. Moreover, I find it is highly important to have this radial field shape distortion, if it may be so termed, a function of time and created very rapidly near the inception of the operative period of the induction accelerator.

In the particular embodiment of my invention illustrated here I secure this time-dependent radial field shape by a coil comprising two turns of wire here identified as 20a and 20b (see Figures

2, 4 and 6). While the radius of these turns may be smaller or larger with a retention of beneficial effects, I prefer to choose a radius such that the lines of magnetic force passing through the center of the wires (when they are open circuited) will pass through the equilibrium orbit, this being a slightly smaller radius than that of the orbit due to the curvature of the magnetic lines of force in a vertical plane. By using this coil 20 as the secondary of a transformer having the coils 17 and 18 as a primary, in effect, a circuit connected to the coil 20 will cause disturbance in the relative radial field strength distribution or radial field shape which is a function of conditions in such circuit, shifting lines of force which would have passed inside the coil to the area outside the turns 20a and 20b; i. e., distorting what might be termed the "static" magnetic radial field shape in such manner that the field strength immediately within the equilibrium orbit is reduced and that without it increased. This change in field shape from the smooth radial field shape curve heretofore provided by design in accordance with the above proportionality (see Figure 2 of the October 1942 article entitled "The betatron" mentioned heretofore, for example) causes the electron to accelerate in toward the equilibrium orbit much more quickly in its initial couple of turns, accelerators embodying this invention increasing the yield 50% or more. Once the electron gets into the equilibrium orbit or swings within it on its radial oscillations, the electron encounters a sharply lower field strength tending to return it more quickly to the equilibrium orbit, so that any variation in radial field shape not only results in getting the electron away from the injector gun structure in the required length of time to avoid unduly large loss of electrons but also results in much greater radial stability of the electron in its subsequent acceleration period during its revolutions in its circular path.

Referring now more particularly to Figure 6, the two turns 20a and 20b of the field shape changing coil 20 are shown as connected in series with the output leads of the coils connected to a circuit including a thyratron 22, which may be of tube type No. FG-154, a resistor 23, a condenser 24, and another resistor 25 in parallel with the condenser. Excitation of the thyratron at the proper interval is effected through lead wires 26a and 26b leading to a peaking strip or any other appropriate source of energizing voltage synchronized with the rise and fall of the main magnetic field in the accelerator. The lead 26b is connected directly to the cathode of the tube 22 and the lead 26a is connected to the grid of such tube through a resistor 27 and bias means here indicated as a bias battery 28. The coil 20 is divided into two turns, with one located on each side of the tube, in order to secure balanced effects on the field. It is preferably kept to only two turns, and must be kept to a low number of turns, in order to get the maximum rate of current change in the coil upon change in the magnetic field about it, to give the desired speed of distortion or change of the radial field shape. The lowest possible number of turns gives the maximum rate of current change in the coil, and thus the maximum change of magnetic field about it, since the voltage developed in the coil only goes down in direct ratio to the number of turns while the inductance drops as the square of the reduction of turns. While a series connection of the two

coil halves 20a and 20b is shown it is understood that a parallel connection could be used if a different circuit arrangement were connected to the coil, and particularly if an appreciable part of the resistance in the circuit were in the connection between the two coil parts.

In the particular circuit illustrated the resistor 23 is given a value in accordance with the peak currents to be permitted to circulate in this circuit, and this value should be of the order of 10 ohms in the particular accelerator being described. The capacity of the condenser 24 is then made such that the time constant or decay constant of the resistor-condenser combination 23 and 24 will be of the order of 100 microseconds, which is approximately the period of time throughout which the device can have desirable effects in the accelerator being described. The value of resistor 25 is chosen such that the time constant of the combination 24 and 25 is large compared with that mentioned in the previous sentence but small compared with the period of one cycle at the frequency at which the accelerator is being operated, as 1/180 second. The time constant of this latter combination must be much larger than that of the first in order that current delivered through the resistor 23 will charge the condenser during the rising portion of the magnetic cycle; and having the time constant of the second combination considerably smaller than the period of one cycle assures discharging of the condenser 24 before the beginning of the next operative period. The condenser 24 and the resistor 25 can be eliminated altogether, and the desired control of current in the coil 20 effected by the resistor 23; this requires a much heavier-duty thyratron. While other types of circuit arrangements and connections to the coil 20 may be made these preferably include some means for having the coil open circuited at the instant of beginning of the rising portion of the positive current flow in the magnet windings, for closing the circuit (as by actuation of the thyratron) at the time of electron injection, and for limiting the current flow in the coil so that the relative effect of this radial field shape-changing arrangement decreases as the power in the main magnet arrangement rises toward maximum. In the particular circuit here being described, for example, the power in the thyratron circuit is limited to about 500 watts, whereas the power circulating in the magnet coils is of the order of 2,000 kva. The power circulating in the thyratron circuit, and its effect on the radial field shape at and about the equilibrium orbit, is very substantial in the early portion of the operative quarter cycle, but substantially negligible near the end thereof. Grid excitation for the thyratron can be from the same source used to actuate the injector circuit, also containing a thyratron control arrangement, or by a separate peaking strip or voltage source between the poles of the accelerator magnet, so that the relative time of firing of the field control thyratron 22 and the injector circuit thyratron can be controlled.

By the use of a radial field shape control arrangement of this kind, the field shape curve can be modified, particularly at and about the equilibrium orbit, so that it may be expressed as a proportionality where

$$H \propto \frac{1}{r^n}$$

where n is not a constant, but a function both of n and of time, this function being such that

the electrons projected into the tube are initially subjected to a high relative radial field strength variation from what is being termed the "static" field condition, and wherein this differential is substantially reduced. This effect should preferably be held within limits such that the field strength of an increment immediately outside the equilibrium orbit never exceeds the field strength of an increment immediately within the equilibrium orbit, but wherein the differential from the smooth curve which would normally be provided by the tapered or diverging pole pieces is considerable, differential being here spoken of as a difference from the radial magnetic field shape which would be produced if my invention were not employed.

While I have shown and described certain embodiments of my invention, it is to be understood that it is capable of many modifications. Changes, therefore, in the construction and arrangement may be made without departing from the spirit and scope of the invention as disclosed in the appended claims.

I claim:

1. A magnetic induction accelerator for charged particles, comprising: a closed vessel defining an annular chamber within which such particles may move in a circular path; a magnetic structure outside said vessel and comprising opposed, generally circular pole pieces which are coaxial with said annular chamber, said pole pieces being of outwardly tapered configuration and having additional field-influencing apparatus associated therewith such that the magnetic field strength varies inversely with the radial displacement r , at and about said path; according to the proportionality

$$H \propto \frac{1}{r^n}$$

where n is a rapidly changing variable, at least at the time charged particles are injected; means for producing a time-varying magnetic field between said pole pieces; and means for projecting charged particles within the annular chamber with a substantial initial velocity.

2. A magnetic induction accelerator for charged particles, comprising: a closed vessel defining an annular chamber within which such particles may move in a circular path; a magnetic structure outside said vessel and comprising opposed, generally circular pole pieces which are coaxial with said annular chamber, said pole pieces being of outwardly tapered configuration and having additional field-influencing apparatus associated therewith such that the magnetic field strength varies inversely with the radial displacement r , at and about said path, according to the proportionality

$$H \propto \frac{1}{r^n}$$

where n is a rapidly changing variable less than unity, at least at the time charged particles are injected; means for producing a time-varying magnetic field between said pole pieces, the arrangement being such that n approaches a constant as the magnetic field between said pole pieces increases; and means for projecting charged particles within the annular chamber with a substantial initial velocity.

3. A magnetic induction accelerator for charged particles, comprising: a closed vessel defining an annular chamber within which such particles may move in a circular path; a mag-

netic structure outside said vessel and comprising opposed, generally circular pole pieces which are coaxial with said annular chamber, said pole pieces being of outwardly tapered configuration and having additional field-influencing apparatus associated therewith, said apparatus being energized at least at the beginning of the operative period and influencing the field such that the magnetic field strength varies inversely with the radial displacement r , at and about said path, according to the proportionality

$$H \propto \frac{1}{r^n}$$

where n is a rapidly changing variable less than unity and has an instantaneous value which is a function both of time and of r at least at the time charged particles are injected; means for producing a time-varying magnetic field between said pole pieces; and means for projecting charged particles within the annular chamber with a substantial initial velocity.

4. In a magnetic induction accelerator for charged particles, comprising a closed vessel defining an annular chamber within which such particles may move in a circular path, a magnetic structure outside said vessel and comprising opposed, generally circular pole pieces which are coaxial with said annular chamber, said pole pieces being of outwardly tapered configuration to produce a predetermined relative radial field strength relationship, means for producing a time-varying magnetic field between said pole pieces, means for projecting charged particles within the annular chamber with a substantial initial velocity, means for varying the relative radial field strength at and about said path as a function of time, including: a coil with a very small number of turns between said pole faces, this coil being coaxial with said circular path and of substantially the same radius means for completing a circuit including said coil in predetermined relation to the changes of the time-varying field to energize said coil during the time particles are projected within said chamber; and means for limiting the current flow in said coil.

5. In a magnetic induction accelerator for charged particles, comprising a closed vessel defining an annular chamber within which such particles may move in a circular path, a magnetic structure outside said vessel and comprising opposed, generally circular pole pieces which are coaxial with said annular chamber, said pole pieces being of outwardly tapered configuration to produce a predetermined relative radial field strength relationship, means for producing a time-varying magnetic field between said pole pieces, means for projecting charged particles within the annular chamber with a substantial initial velocity, means for varying the relative radial field strength at and about said path as a function of time, including: a coil with a very small number of turns between said pole faces, this coil being coaxial with said circular path and of substantially the same radius; a circuit connected to said coil, this circuit including a gas filled, grid controlled triggering tube and current limiting means; and apparatus rendering said tube conductive at the beginning of a period of rising magnetic field strength.

6. In a magnetic induction accelerator for charged particles, comprising a closed vessel defining an annular chamber within which such particles may move in a circular path, a mag-

netic structure outside said vessel and comprising opposed, generally circular pole pieces which are coaxial with said annular chamber, said pole pieces being of outwardly tapered configuration to produce a predetermined relative radial field strength relationship, means for producing a time-varying magnetic field between said pole pieces, means for projecting charged particles within the annular chamber with a substantial initial velocity, means for varying the relative radial field strength at and about said path as a function of time, including: a coil with a very small number of turns between said pole faces, this coil being coaxial with said circular path and of substantially the same radius; a circuit connected to said coil, this circuit including a gas filled, grid controlled tube connected directly to said coil and current limiting means comprising a resistor and a condenser; and apparatus rendering said tube conductive at the beginning of a period of rising magnetic field strength.

7. In a magnetic induction accelerator for charged particles, comprising a closed vessel defining an annular chamber within which such particles may move in a circular path, a magnetic structure outside said vessel and comprising opposed, generally circular pole pieces which are coaxial with said annular chamber, said pole pieces being of outwardly tapered configuration to produce a predetermined relative radial field strength relationship, means for producing a time-varying magnetic field between said pole pieces, means for projecting charged particles within the annular chamber with a substantial initial velocity, means for varying the relative radial field strength at and about said path as a function of time, including: a coil with a very small number of turns between said pole faces, this coil being coaxial with said circular path and of substantially the same radius; a circuit connected to said coil, this circuit including a gas filled, grid controlled triggering tube connected directly to said coil and current limiting means; and apparatus rendering said tube conductive at the beginning of a period of rising magnetic field strength, the coil having a substantial effect on the relative radial field strength at the beginning of the period of rising magnetic field strength and negligible effect thereon near the end of said period.

8. A method of bringing a group of charged particles to a desired velocity in a desired path, comprising initially accelerating said charged particles by a first force, radially accelerating said charged particles to cause them to tend to travel in a circular path and accelerating their velocity in such path by another force, and rapidly varying the relative radial accelerating force at least at the beginning of the operative period, as a function of time.

9. A method of bringing a group of charged particles to a desired velocity in a desired path, comprising initially accelerating said charged particles by a first force, and both radially accelerating said charged particles to cause them to tend to travel in a circular path and accelerating their velocity in such path by a varying magnetic force, this being a different force than said first force, and rapidly varying the radial accelerating component of said magnetic force, at least at the beginning of the operative period, as a function of time, relative to the accelerating component at right angles thereto.

10. A method of bringing a group of charged particles to a desired velocity in a desired path,

comprising initially accelerating said charged particles by an electrostatic force, and both radially accelerating said charged particles to cause them to tend to travel in a circular path and accelerating their velocity in such path by a varying magnetic force, and rapidly varying the relative radial field strength, at least at the beginning of the operative period, as a function of time.

11. A method of bringing a group of charged particles to a desired velocity in a desired path, comprising initially accelerating said charged particles by an electrostatic force, and both radially accelerating said charged particles to cause them to tend to travel in a circular path and accelerating their velocity in such path by a varying magnetic force, and varying the relative radial field strength as a function of time, this variation being so arranged as to provide greater relative radial field strength variations at and about the desired path near the beginning of the accelerating period than later in said period.

12. A magnetic induction accelerator for charged particles, comprising: a closed vessel defining an annular chamber within which such particles may move in a circular path; a magnetic structure outside said vessel and comprising opposed, generally circular pole pieces which are coaxial with said annular chamber; means for producing a time-varying magnetic field between said pole pieces; means for projecting charged particles within the annular chamber with a substantial initial velocity; and conducting apparatus in said magnetic field affecting the radial position of said charged particles at least at the beginning of the operative period, said conducting apparatus being operable to vary the relative radial field strength, at least at the beginning of the operative period, as a function of time.

13. A magnetic induction accelerator for charged particles, comprising: a closed vessel defining an annular chamber within which such particles may move in a circular path; a magnetic structure outside said vessel and comprising opposed, generally circular pole pieces which are coaxial with said annular chamber, said pole pieces being of outwardly tapered configuration to produce a predetermined relative radial field strength relationship; means for producing a time-varying magnetic field between said pole pieces; means intermittently operative for projecting charged particles within the annular chamber with a substantial initial velocity; and conducting apparatus in said magnetic field affecting the radial position of said charged particles at least at the beginning of the operative period, said conducting apparatus being operable to vary the relative radial field strength at and about said path as a function of time, and initially to subject the projected particles to a

rapidly created high relative radial field strength differential and subsequently to reduce such differential.

14. A magnetic induction accelerator for charged particles, comprising: a closed vessel defining an annular chamber within which such particles may move in a circular path; a magnetic structure outside said vessel and comprising opposed, generally circular pole pieces which are coaxial with said annular chamber, said pole pieces being of outwardly tapered configuration to produce a predetermined relative radial field strength relationship; means for producing a time-varying magnetic field between said pole pieces; means intermittently operative for projecting charged particles within the annular chamber with a substantial initial velocity; and apparatus affecting the radial position of said charged particles at least at the beginning of the operative period, this apparatus comprising a coil with a very small number of turns between said pole faces and coaxial with said circular path, and a circuit for energizing said coil to vary the relative radial field strength at and about said path, at least at the beginning of the operative period, as a function of time.

15. A magnetic induction accelerator for charged particles, comprising: a closed vessel defining an annular chamber within which such particles may move in a circular path; a magnetic structure outside said vessel and comprising opposed, generally circular pole pieces which are coaxial with said annular chamber, said pole pieces being of outwardly tapered configuration to produce a predetermined relative radial field strength relationship; means for producing a time-varying magnetic field between said pole pieces; means intermittently operative for projecting charged particles within the annular chamber with a substantial initial velocity; and apparatus affecting the radial position of said charged particles at least at the beginning of the operative period, this apparatus comprising a coil with a very small number of turns between said pole faces and coaxial with said circular path and of substantially the same radius as said path, and a circuit for energizing said coil to vary the relative radial field strength at and about said path, at least at the beginning of the operative period, as a function of time.
